UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,396,517.

Specification of Letters Patent.

Patented Nov. 8, 1921.

Application filed August 2, 1919. Serial No. 314,950.

To all whom it may concern:

Be it known that I, WILLIAM L. MCGRATH, a citizen of the United States, residing at Elmira, in the county of Chemung 5 and State of New York, have invented certain new and useful Improvements in Engine-Starters, of which the following is a specification.

My invention relates to a starter drive for 10 gasoline engines and the like and of the general type known as the Eclipse-Bendix drive which is characterized by a rotatable driving shaft such as a screw shaft and a driving member such as a pinion screw 15 threaded thereon for longitudinal movement thereof and rotary movement therewith, and adapted to operate directly or indirectly a member of the engine to be started. This drive is further characterized by a yielding 20 driving connection such as a drive spring between such screw shaft and a driving shaft operated by a prime mover such as an electric motor. The object of my invention is to provide a construction of drive and 25 associated or supporting parts which will be compact and occupy a minimum of space, and also permit of the use of a pinion provided with a minimum number of teeth whereby the pinion may be reduced to the 30 smallest diameter. The drive itself is so constructed that a considerable portion thereof is inclosed within its supporting housing or mounting and only that portion such as the pinions and a part of the screw 35 shaft projects therebeyond for connection with the engine member such as the flywheel.

In the drawings Figure 1 is a sectional 40 elevation of an engine starter embodying my invention; and Fig. 2 a similar view of a modified form of construction.

Referring to the embodiment of my invention as shown in Fig. 1 the prime mover which is an electric motor 1 has an extended 45 armature shaft 2 which projects beyond the end of the motor and to which the drive hereinafter described is attached and by which it is driven. To the end of the motor a drive housing or mounting 3 is secured in suitable manner as by means of the screws 4. This housing and also the motor if not otherwise supported, is by preference 50 supported in a fixed part of the engine such as the crank case, a portion of which is indicated at 5. The housing is secured within

this main support 5 in proper position both axially and angularly in suitable manner as by means of the screw bolt 6 screwing into said support 5 and having a tapered end 7 adapted to engage a similarly tapered hole 60 8 in the side of the housing 3. This bolt thus locks and secures the housing in its proper position within its support. This bolt is provided with a lock nut 9.

The housing 3 contains a part of the drive 65 or transmission, the remaining part being the screw shaft and the pinion. Describing the drive as herein shown, a driving head or collar 10 is secured to the shaft 2 by means of the bolt 11. This driving head 70 is secured to a driven head 12 by means of the driving spring 13 one end of which is anchored to the driving head 10 by the bolt 11 and the other end to the driven head 12 by the bolt 14. This latter head 12 is 75 mounted loosely upon the shaft 2 and its central bore is screw threaded for a portion of its length at 15 and into such latter bore is screwed the screw shaft 16. A projection 17 on the driven head 12 acts as a stop 80 nut for the pinion. The driven head 12 is supported by the housing 3 in the opening 18 forming a bearing for the drive.

The driving member which is here a pinion 19 is screw threaded upon the shaft 85 16 and has a portion of its outer end cut away so as to provide an over-balancing or weighted portion 20, the ends of the screw threads forming positive stops as usual for the pinion in its return to normal position. 90 This pinion is adapted to mesh with the engine member which is here indicated as the flywheel 22.

Describing a cycle of operation and starting with the parts in the normal position 95 shown, when the motor is operated and the shaft 2 thereby rotated, the torque will be transmitted to the drive through the driving head 10, spring 13, head 12 and screw shaft 16, with the result that the pinion will 100 be automatically advanced longitudinally to the left into mesh with the flywheel. When this longitudinal movement is arrested by the stop 17 the pinion will partake of the rotary movement of its shaft and the flywheel will 105 be rotated and the engine started. When the engine has started on its own power the pinion will be automatically demeshed and returned to the normal position shown.

The described construction is very com- 110

pact and so made as to be associated with and practically embodied as a part of its housing and mounting, leaving exposed only that which is absolutely necessary to be extraneous such as the pinion and a portion of the screw shaft.

In Fig. 2 I have shown a modified form of construction according to which the housing or mounting 23 of the drive is secured to and 10 is self-supported by the motor 24, being attached thereto in suitable manner as by means of the bolts 25. The construction of the drive is substantially the same as that already described except that the screw shaft 15 may or may not be an integral part of the driving head 12.

I claim:

1. The combination, with a prime mover and its driving shaft, of a housing secured 20 thereto and having a supporting bearing, and a drive comprising a driving head connected with the driving shaft and located within the housing, and supported by said supporting bearing, a rotatable shaft connected 25 with such head and projecting beyond said housing, said rotatable shaft being not substantially larger in diameter than the driving shaft and in axial alinement therewith, and a driving member mounted 30 upon the rotatable shaft and having a longitudinal movement thereof and rotary movement therewith.

2. The combination, with a prime mover and its driving shaft, of a housing secured 35 thereto and having a supporting bearing, and a drive comprising a driving head connected with the driving shaft and located within the housing and supported by said supporting bearing, a rotatable shaft 40 detachably connected with such head and projecting beyond said housing, said detachable shaft being in axial alinement with the shaft of the prime mover, and a driving member mounted upon the rotatable shaft and having a longitudinal movement thereof and rotary movement 45 therewith.

3. The combination, with a prime mover and its driving shaft, of a housing secured thereto and having a supporting bearing,

and a drive comprising a driving head secured to the driving shaft, a second driving head having a central bore whereby it is mounted upon such shaft, yielding driving means connecting the two heads, such heads and the yielding driving means being located 50 within the housing and the second head being supported by said bearing of the housing, a rotatable shaft secured in said bore of the second head and projecting beyond said housing, and a driving member mounted 55 upon the rotatable shaft and having a longitudinal movement thereof and rotary movement therewith.

4. In an engine starter drive, the combination, with an electric motor, and its driving 60 shaft, of a housing secured to the motor and having a bearing, and a drive comprising a driving head connected with the driving shaft and located within the housing and supported by said bearing, said head having 65 a central bore whereby it is mounted upon the driving shaft, a screw shaft connected with such head and projecting beyond said housing, said screw shaft being secured in said bore of the head and in axial 70 alinement with the driving shaft, and a pinion threaded on the shaft for longitudinal 75 movement thereof and rotary movement therewith.

5. The combination of a prime mover and 80 its driving shaft, of a housing secured thereto and having a supporting bearing, a main support for such housing, means for locating and securing the housing in such support, and a drive comprising a driving 85 head connecting with the driving shaft and located within the housing and supported by said bearing, a rotatable shaft connected with such head and projecting beyond said housing, and a driving member mounted 90 upon the rotatable shaft and having a longitudinal movement thereof and rotary movement therewith, said locating and securing means comprising a bolt screw-threaded into the main support and having a tapered end, 95 said housing having a tapered hole to receive said end.

WILLIAM L. McGRATH.
